UNITED STATES PATENT OFFICE.

ADOLPH ROSENTHAL, OF AUGUSTA, GEORGIA.

BABY-WALKER.

SPECIFICATION forming part of Letters Patent No. 427,116, dated May 6, 1890.

Application filed November 11, 1889. Serial No. 329,891. (No model.)

To all whom it may concern:

Be it known that I, ADOLPH ROSENTHAL, a citizen of the United States, residing at Augusta, in the county of Richmond, State 5 of Georgia, have invented certain new and useful Improvements in Baby-Walkers, of which the following is a specification, reference being had therein to the accompanying drawings.

10 The objects of my invention are to provide convenient means for assisting a child to walk and amuse itself, and at the same time provide a seat permanently attached thereto by means of hinged straps and hinges for the 15 child, when required, and also to provide means for adapting the chair for the use of a large or small child, and in connection with an undivided top, consisting of a single board centrally perforated, provide means for filling a portion of the opening by a sliding board having a segment removed therefrom and adjustably connected with the frame of 20 the device. I attain these objects by the construction illustrated in the accompanying drawings, in which—

Figure 1 is a vertical section of a baby-walker constructed in accordance with my invention. Fig. 2 is a vertical section of the same at right angles to Fig. 1. Fig. 3 is a top 30 view of the same. Fig. 4 is a bottom view of the same.

In said drawings, A represents a rectangular frame supported by and to which are attached the four legs B. Each of said legs is 35 formed in two parts adapted to slide the one upon the other by a bolt b passing through vertical slots in said parts, so that the height of the device can be adapted for the use of a large or small child. To the top of the frame 40 A is attached an undivided top C, having a central round opening C², of such diameter as to be capable of receiving the body of a large child. The top C, being made in one piece and undivided, forms a strong connection for 45 the four sides of the frame and prevents racking of said parts; but to apparently reduce the size of the opening C² a board D is placed under the top C and has its ends received between slats a and a², secured to the frame 50 A. Said board has a segment cut out of its inner edge corresponding with a portion of the periphery of the opening C². The board

D can be moved in and out within certain limits by hand, either from the under side or from its inner edge, or by means of a tongue 55 or strap d attached to its outer edge. The board D is adjustably connected to the top C and retained in its adjusted position by means of a bolt E, passing through said top and through the slats a a², and a thumb-nut e upon 60 said bolt, the bottom slat a² springing sufficiently under the pressure of the bolt and nut to clamp one end of the board D, said end being slotted or recessed at d² for the passage 65 of the bolt.

To provide the device with a seat for the child, two of the legs are united by a strip B², to which the rear end of the seat F is permanently united by means of hinges f.

The seat is suspended from the top C by 70 means of the folding metal straps g, pivotally attached to said top and to the front corners of the seat, the said straps being hinged at g², so that the seat can be folded and made to occupy a vertical position, as shown by dotted 75 lines in Fig. 1. The straps, having somewhat stiff hinges, will retain the seat in said folded position. The seat and the edge of the opening in the top C and in the board D can be upholstered or padded, as shown. 80

The baby-walker can be transformed into a stool by the addition of a top board H, (shown lifted in Fig. 1,) having central projection to fit in the opening C², and turn-buttons h, secured to the bottom of said projection and adapted to engage under the top C. 85

Having now fully described my invention, I claim—

In a baby-walker, the combination of the frame A, its legs, and strip B², uniting two of 90 them, and the undivided top C, supported on said frame, with the seat F, having the rear end hinged to said strip, and the straps g, having one end hinged to the top C, the other end hinged to the seat, and a hinge g² between said straps, the seat being adapted to be folded upward, substantially as and for 95 the purpose described.

In testimony whereof I affix my signature in presence of two witnesses.

ADOLPH ROSENTHAL.
